DESIGN FOR A DISPLAY RACK FOR PIECE GOODS BOLTS

Simon P. Brown, New York, N. Y.

Application November 10, 1939, Serial No. 88,193

Term of patent 14 years

To all whom it may concern:

Be it known that I, Simon P. Brown, a citizen of the United States and a resident of the city, county, and State of New York, have invented a new, original, and ornamental Design for a Display Rack for Piece Goods Bolts, of which the following is a specification, reference being had to the accompanying drawing, forming part

thereof, in which the figure is a perspective view of a display rack for piece goods bolts, showing my new design.

I claim:

The ornamental design for a display rack for piece goods bolts, substantially as shown.

SIMON P. BROWN.
